UNITED STATES PATENT OFFICE.

OSCAR J. ZIEGLER, OF FREEPORT, ILLINOIS, ASSIGNOR TO THE STOVER MANUFACTURING COMPANY, OF SAME PLACE.

GRINDING-MILL.

SPECIFICATION forming part of Letters Patent No. 634,052, dated October 3, 1899.

Application filed March 31, 1899. Serial No. 711,264. (No model.)

To all whom it may concern:

Be it known that I, OSCAR J. ZIEGLER, a citizen of the United States of America, residing at Freeport, in the county of Stephenson and State of Illinois, have invented certain new and useful Improvements in Grinding-Mills, of which the following is a specification.

My invention relates to improvements in mills of the class commonly known as "feed-grinders," and is fully described and claimed hereinafter.

Referring to the accompanying drawings, which form a part of this specification, Figure 1 is an isometrical view of a mill embodying my improvements. Fig. 2 is a central vertical section of the mill shown in Fig. 1. Fig. 3 is a like view of the same with some of the parts thereof in different positions from those shown in Fig. 2. Figs. 4, 5, and 6 are detail views hereinafter fully described.

A is a ground-feed receptacle of any desired form and construction.

B is the base of the mill, having countersunk thereinto a circular geared track B' and a circular smooth track B² and provided with openings B³, extending vertically therethrough, to allow any portion of the ground feed that may chance to work thereinto from the grinding-burs when the mill is operated to pass downward thereout.

B⁴ is an outside grinding-bur provided with an upwardly-projecting annular flange B⁵ and spider B⁶, having a vertical opening B⁷ in the apex thereof and rigidly connected with the base B.

C is a master-ring having horizontal stub-axes C' projecting radially inward from the inside thereof.

C² are pinions mounted on the stub-axes C' and meshing with the circular geared track B', countersunk into the base B of the mill.

C³ are antifriction-rollers mounted on the stub-axes C', concentrical and preferably integral with the pinions C², and adapted to traverse the smooth circular track B², countersunk into the base B of the mill.

C⁴ are lugs to which a sweep (not shown) for rotating the master-ring C may be attached.

D is an inside grinding-bur, the counter-

part of the outside grinding-bur B⁴, provided with a countersunk mortise D' in the upper central portion thereof.

E is a driving-ring having countersunk into the under face thereof a circular geared track E', adapted to mesh with the pinions C², and a circular smooth track E², adapted to admit and engage the peripheries of the antifriction-rollers C³, provided with an annular flange E³, projecting downward therefrom within the upwardly-projecting annular flange B⁵ on the part B⁴, and a spider E⁴, supporting a downwardly-extending tenon E⁵, adapted to enter the mortise D' in the part D.

F is a gear-guarding cylinder rigidly secured at its upper end to the under face of the driving-ring E and projecting downwardly therefrom between the outside grinding-bur B⁴ and the master-ring C and countersunk geared track B' in the base B of the mill to the vertical openings B³, extending therethrough.

G is a yoke resting upon the spider E⁴ of the driving-ring E.

H is a long bolt extending vertically through the parts D' E⁵ E⁴ G, whereinto it is secured by means of the lever-nut J. The bolt H suspends the inside grinding-bur D from the driving-ring E, and the lever-nut J serves to adjust the inside and outside grinding-burs B⁴ D by drawing them into closer proximity, or vice versa.

The collar K and bolts and nuts K' K² secure the driving-ring E into engagement with pinions C².

The countersink in the base B is constructed, as shown in Figs. 2 and 3, to adapt it for use as a track-tank for oil, and when filled therewith it lubricates the pinions C² and the upper and lower geared tracks B' E', meshing therewith, and the antifriction-rollers C³ and the upper and lower smooth tracks B² E², in contact therewith.

The purpose of the upwardly-projecting flange B⁵ on the outside grinding-bur B⁴ and the downwardly-projecting flange E³ on the driving-ring E is to prevent the grain being ground from escaping between such grinding-bur B⁴ and driving-ring E. Unavoidably, however, sometimes a small quantity of

ground feed does escape between the flanges B⁵ E³. In that event the gear-guarding cylinder F prevents it from getting into the gears, geared tracks, antifriction-rollers, and their tracks, and it passes by the operation of gravity and by reason of the vibrations of the running mill downward between the outside grinding-bur B⁴ and gear-guarding cylinder F and outward through the vertical openings B³ in the base B of the mill.

The antifriction-rollers C³ render the mill light running, and thus easy to operate, and the pinions C² serve not only to communicate power from the master-ring C to the driving-ring E and thence to the inside grinding-bur D, but they also operate to speed them to a velocity double that of the master-ring C.

The parts B C E F are so formed and arranged as to produce a complete inclosure for the pinions and antifriction-rollers C² C³ and their tracks, thereby protecting them and the circular tank of oil they run in from dust, dirt, and other foreign substances.

I claim—

1. In a grinding-mill, in combination, a base having countersunk thereinto a circular geared track and a circular smooth track, a master-ring having horizontal stub-axles projecting radially inward from the inside thereof and provided with pinions, meshing with the circular geared track, and with antifriction-rollers, adapted to traverse the circular smooth track, a driving-ring having countersunk into the under face thereof a circular

geared track, adapted to mesh with the pinions, and a circular smooth track, adapted to admit and engage the peripheries of the antifriction-rollers, and a gear-guarding cylinder, rigidly secured, at its upper end, to the under face of the driving-ring and projecting downwardly therefrom to the mill-base, substantially as and for the purpose specified.

2. In a grinding-mill, in combination, a base having countersunk thereinto a circular geared track and a circular smooth track and provided with vertical openings extending therethrough, a master-ring having horizontal stub-axles projecting radially inward from the inside thereof, pinions and antifriction-rollers mounted thereon, the former meshing with the geared track and the latter adapted to traverse the smooth track of the base, a driving-ring having countersunk into the under face thereof a circular geared track and a circular smooth track, the former meshing with the pinions and the latter adapted to admit and engage the peripheries of the antifriction-rollers, a gear-guarding cylinder, rigidly secured, at its upper end, to the under face of the driving-ring and projecting downwardly therefrom to the vertical openings in the mill-base, and the outside and inside grinding-burs, substantially as and for the purpose specified.

OSCAR J. ZIEGLER.
